UNITED STATES PATENT OFFICE.

EDWARD BAUER, OF WEST NEW YORK, AND PHILIP MIOZZI, OF UNION CITY, NEW JERSEY.

LOOM.

Application filed April 5, 1926. Serial No. 99,887.

This invention relates to improvements in looms and has for its primary object the provision of means for producing a slack in the warp threads at each operation of the loom harness and thus eliminate the stretching of the threads and possible injury thereto as the threads are separated for the passage of the shuttle.

More specifically stated, the invention provides means for automatically moving the whip roller at each operation of the loom harness so as to produce the desired slack of the warp threads as the latter are separated for the shuttle and to subsequently render the threads taut, the pivotal movement of the whip roller being governed by the operation of the lay.

With the above and other objects in view, the invention further includes the following novel features and details of construction, to be hereinafter more fully described, illustrated in the accompanying drawings and pointed out in the appended claim.

In the drawings:—

Figure 1 is a fragmentary side view of a dobby loom with the invention applied, parts being diagrammatically illustrated.

Figure 2 is an enlarged fragmentary section on the line 2—2 of Figure 1.

Figure 3 is a detail view of the roller arm pivot.

Figure 4 is a similar view of the pivot for adjustably connecting the whip roller arm with the connecting rod.

Referring to the drawings in detail wherein like characters of reference denote corresponding parts, the reference character 10 indicates the frame of the loom, 11 the lay, 12 the lay leg and 13 the loom harness, while the warp bar is indicated at 14. The warp threads 15 pass from the bar 14 over the whip roller and through the harness to the lay in the ordinary manner, except that the whip roller 16 instead of being mounted in

stationary bearings, is mounted in pivotally movable bearings and the latter are moved by the operation of the loom so as to produce a slack in the warp threads 15.

Where the bearings for the whip roller

are stationary, operation of the loom harness in separating the warp threads for the passage of the shuttle, will stretch the said threads and frequently these threads are broken. The present invention overcomes this disadvantage by producing a slack in the threads as the latter are separated so that they are relieved of strain. To accomplish this the whip roller 16 is mounted in the upper ends of bearings 17, one of which is provided at each side of the frame 10. These arms are adjustably and pivotally mounted upon pivot pins 18, the frame 10 being provided with slots 19 to permit of longitudinal adjustment.

The lower ends of the arms 17 are longitudinally slotted as shown at 20 and passing through the slots of these arms are pivot bolts 21. The bolts 21 serve to pivotally and adjustably connect the lower ends of the arms 17 with rods 22, the latter being provided with loops 23 for this purpose. The pivotal connection between the arms 17 and rods 22 may thus be adjusted while the loops 23 are threadedly and adjustably mounted upon the rods 22.

The opposite ends of the rods 22 are adjustably secured to the lay legs 12 by means of clamps 24, the latter carrying studs 25 upon which the rods 22 are pivotally mounted.

It will be apparent from the foregoing description and accompanying drawings that at each pivotal movement of the lay legs, the arms 17 will be simultaneously moved, movement of the lay and whip roller being relatively inward or toward one another so as to produce a slack in the warp threads.

The invention is susceptible of various changes in its form, proportions and minor details of construction and the right is here reserved to make such changes as properly fall within the scope of the appended claim.

Having described the invention what is claimed is:—

A loom comprising a slotted frame, a swingable lay having legs pivotally connected at their lower ends to said frame,

arms remote from the lay and pivotally connected at intermediate points in their lengths to the slotted frame and having longitudinally-slotted lower portions, a whip roller mounted between the upper ends of said arms, and rods connected to and adjustable on the legs of the lay and the lower portions

of the arms and interposed directly between said legs and arm portions.

In testimony whereof we affix our signatures.

EDWARD BAUER.
PHILIP MIOZZI.
